UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

IRONING-MACHINE.

1,133,620.

Specification of Letters Patent. Patented Mar. 30, 1915.

Application filed February 16, 1912. Serial No. 677,943.

To all whom it may concern:

Be it known that I, DANIEL M. COOPER, of Rochester, in the county of Monroe and State of New York, have invented certain new and useful Improvements in Ironing-Machines; and I do hereby declare the following to be a full, clear, and exact description of the same, reference being had to the accompanying drawings, forming a part of this specification, and to the reference-numerals marked thereon.

The present invention relates to improvements in ironing machines, of the particular type embodying a pair of rotatable ironing rolls, one arranged to be moved into and out of engagement with the other, and it has for its object to provide an improved construction and arrangement of parts which will enable the more ready operation of the machine, permitting perfect control, and easier action of the parts.

A further object of my improvement is to provide a simple and improved means for enabling the adjustable roll to be moved toward and from the other roll by fluid pressure.

To these and other ends the invention consists in certain improvements and combinations of parts, all as will be hereinafter more fully described, the novel features being pointed out in the claims at the end of the specification.

In the drawings: Figure 1 is a view in side elevation, with parts in section, and a portion broken away, showing an ironing machine constructed in accordance with a preferred embodiment of my invention; Fig. 2 is a sectional view on the line 2—2 of Fig. 1; Fig. 3 is a sectional view showing the construction of the pressure cylinder and piston, and controlling valve, with its operative connections; Fig. 4 is a detail sectional view showing the transmission shaft, and the arrangement of pulleys thereon; Fig. 5 is a sectional view on the line 5—5 of Fig. 1; Fig. 6 is a sectional view on the line 6—6 of Fig. 5; Fig. 7 is a sectional view on the line 7—7 of Fig. 1; Fig. 8 is a detail view of the connection between one of the operating members and the actuator for the belt shifter; Fig. 9 is a sectional view on the line 9—9 of Fig. 3, showing the valve open, and

Fig. 10 is a similar view, with the valve closed.

Similar reference numerals throughout the several figures indicate the same parts.

The invention, as illustrated in the present embodiment, comprises a main supporting frame 1 having a base 2. Suitably mounted in the frame are the ironing rolls 3 and 4 arranged above and below one another respectively, the upper roll being fixed against bodily vertical movement, while the lower roll is arranged to be moved into and out of engagement with the upper roll, in a manner to be described presently. The roll 3 is carried by the shaft 5 to which is secured a pinion 6 and a gear wheel 7, while the roll 4 is carried by the shaft 8, one end of which is supported in a suitable bearing 60 pivoted in the frame at 9. The shaft 8 is provided with a pinion 10 for engagement with the aforementioned pinion 6 when moved vertically into engagement therewith, as shown in Fig. 1. The gear wheel 7 is 65 operated from a pinion 11 fixed upon the hollow shaft 12, the latter having keyed thereto a pulley 13. Loosely mounted on said hollow shaft 12 is a pulley 14, and 70 15 is a loose pulley mounted on the bearing 16, as 75 shown in Fig. 4. Belts 17 and 18 running in opposite directions are arranged for co-operation with the pulleys just described, one of said belts being engaged with the fixed pulley and the other of said belts being 80 in engagement with a loose pulley. The position of the belts is controlled by a belt shifter including arms 19 and 20 which are 85 mounted on the rod 21, the latter being operated in a manner that will presently be 90 made clear.

The vertical movement of the lower ironing roll is preferably effected by fluid pressure controlled devices, comprising in the present embodiment a cylinder 22 within 95 which travels a piston 23, the latter having pivoted thereto a connecting rod 24 which is pivoted at its upper end to the links 25 and 26, and to the yoke member 27. The link 25 is pivoted to the supporting 100 frame and the link 26 is in turn pivoted to the upwardly extending rod 28, which at its upper end supports the bearing 29 for the lower ironing roll 4, and to

the supporting link 30 pivotally mounted on the support 31, the latter being held within the frame in any suitable manner, as by means of a bolt 32. The yoke member 27 5 carries a vertical rod 33 movable through an opening in a guide 34, which may be held in the frame in any suitable manner, a spring 35 being arranged on the rod 33 and disposed between the guide 34 and the collar 36. 10 The purpose of this is to prevent sudden jar of the parts upon the downward movement of the piston when the pressure is released, the spring 35 serving to retard such movement and to prevent the piston from 15 coming too violently in contact with the bottom of the cylinder. Upward movement of the piston is effected by a fluid under pressure, and preferably by means of compressed air, which is admitted to the cylinder in any 20 suitable manner from the pipe 37, and in the present embodiment, this is accomplished by means of a rotary valve 38 having a transverse port 39 and a by-pass 40. A passage 41 leads from the valve 38 to the cylinder, 25 while a second passage 42 is connected to the atmosphere to permit the pressure to be exhausted from the cylinder when the valve is closed, at which time the passage 42 is connected with passage 41 by means of the by-pass 40, as shown in Fig. 3. When the valve 30 is turned, as will hereinafter be described, the passage 42 is closed and the port 39 opens communication with passage 41, permitting the compressed air to enter and to 35 raise the piston. It is desirable to limit the admission of pressure during the initial movement of the piston, so that the lower ironing roll may be raised slowly until it is in contact with the upper roll, after which 40 full pressure can be applied to force the rolls into more intimate engagement. To this end, the piston 23 carries a downwardly projecting pin 43 of somewhat less diameter than the passage 41, and provided with a 45 tapered extremity 44. Thus, when the valve is first opened, only a comparatively small amount of pressure can enter the cylinder, the opening being restricted by the position of the pin 43, and as the piston moves upwardly, the tapered portion 44 permits the opening to be gradually enlarged, until full pressure is admitted and the rolls are held in engagement as long as the valve remains open. The cylinder 22 is mounted on the 50 aforementioned support 31, as shown in Fig. 3, said cylinder being provided with the neck 45 to which is attached the valve casing 46. The valve is suitably attached to the rotary stem 47, to the outer end of which is secured an arm 48 having a yoke 49 at its lower end. A shaft 50 is suitably journaled in the extension 51 and carries a crank arm 52, the latter being provided with a crank pin 53 for engagement with the yoke 49.

The shaft 50 carries at its opposite end the pinion 54, which is arranged to be engaged by a gear segment 55 fixedly mounted on the hollow shaft, or operating member 56. The latter has fixed thereon a treadle 57. The lower roll 4 being normally out of engagement with the upper roll, when it is desired to move it upwardly into engagement, the treadle 57 is operated so as to effect opening of the valve 38 and admit pressure to the cylinder. Upon release of the treadle, the valve is returned to its normal closed position by means of a spring 58 which acts upon a rod 59, the latter being connected to the gear segment 55, as shown in Fig. 2.

I have also provided a simple means for effecting reverse movement of the ironing rolls, and to this end, in the present embodiment, the rod 21 is pivotally connected to the angle arm 60, pivoted at 61, and in turn pivotally connected to the vertically disposed rod 62, the latter being adjustably connected at its lower end to a crank arm 63 carried by the operating rod or member 64. The member 64 extends through the hollow operating member 56 and has keyed thereto at its outer end a treadle 65 for operating the same. The operating members 56 and 64 are journaled in a block 66, which is pivotally supported on a transverse post 67 so as to enable it to be adjusted to permit the parts to be lined up properly upon the floor when the machine is set in position. The block 66 is held in adjusted position by means of a suitable bolt 68 passing through the upper slotted portion 69 and engaging in the extension 51 of the support 31. The treadles 57 and 65, previously mentioned, are designed to be engaged by the foot of the operator when in standing position.

To operate a machine of this character in one position for a long period is quite tiresome, and it is desirable to provide a convenient means for enabling the operator to control the machine when sitting down. To this end, supplemental treadles 69 and 70 are provided, which are operatively connected to the treadles 57 and 65, respectively, as shown in Fig. 5, in which 71 is a gear segment formed on the treadle 70 and engaging a corresponding gear segment 72 on the treadle 65. The arrangement and position of the treadles 69 and 70 is such that they can readily be engaged by an operator when sitting on a stool, and the depression of either one of said treadles effects the same operation of the machine as the treadles 57 and 65, either to raise the lower ironing roll, or to reverse the movement of the ironing rolls. The outer ends of the operating members are journaled in bearing 73, constituting part of a casting provided with the feet 74 by which it may be attached to the floor, as seen in Fig. 6.

I claim as my invention:

1. In an ironing machine, the combination with a pair of ironing members, one being movable into and out of engagement with the other, of means for effecting movement of said member comprising a rod operatively connected thereto and to a piston, a cylinder within which the piston travels, a valve for controlling the admission of fluid pressure to the cylinder, and automatically operated means acting to limit the supply of fluid pressure during the initial movement of the piston and to increase the fluid pressure supply during its further movement.

2. In an ironing machine, the combination with a pair of rolls, one of said rolls being movable into and out of engagement with the other roll, of means for effecting movement of said roll comprising a cylinder, a piston movable within the cylinder, operative connections between the piston and the roll, a valve for controlling the supply of fluid pressure to the cylinder, and means carried by the piston for limiting the supply of fluid pressure during the initial movement of the piston and for increasing the supply during its further movement.

3. In an ironing machine, the combination with a pair of rolls, one of said rolls being movable into and out of engagement with the other roll, of means for effecting movement of said roll comprising a cylinder, a piston movable within the cylinder, operative connections between the piston and the roll, a valve for controlling the supply of fluid pressure to the cylinder, said valve and cylinder being connected by a passage, and a pin carried by the piston and adapted to extend into said passage, the pin being provided with a tapered end portion.

4. In an ironing machine, the combination with a pair of rolls, one of said rolls being movable into and out of engagement with the other roll, of means for effecting movement of said roll comprising a cylinder, a piston movable within the cylinder, operative connections between the piston and the roll, fast and loose pulleys arranged on a shaft, gearing between said shaft and the rolls, a pair of belts leading to the pulleys, a belt-shifter controlling the position of the belts to operate the rolls in normal or reverse direction, a fluid pressure supply leading to the cylinder, a valve for controlling the supply of fluid pressure to the cylinder, a hollow operating member oper-

atively connected to the valve, an operating member extending through said hollow member and operatively connected to the belt-shifter, and means for actuating said operating members.

5. In an ironing machine, the combination with a supporting frame, of a pair of rolls journaled in the supporting frame, one of said rolls being movable into and out of engagement with the other roll, means for effecting movement of said roll comprising a cylinder, a piston movable within the cylinder, operative connections between the piston and the roll, fast and loose pulleys arranged on a shaft, gearing between said shaft and the rolls, a pair of belts leading to the pulleys, a belt-shifter for controlling the position of the belts to operate the rolls in normal or reverse direction, a valve controlling the admission of fluid pressure to the cylinder, a hollow operating member operatively connected to the valve, an operating member extending through said hollow member and operatively connected to the belt-shifter, a block adjustably mounted in the frame for holding said operating members, means for holding the block in adjusted position and means for actuating the operating members.

6. In an ironing machine, the combination with a supporting frame, of a pair of rolls journaled in the supporting frame, one of said rolls being movable into and out of engagement with the other roll, means for effecting movement of said roll comprising a cylinder, a piston movable within the cylinder, operative connections between the piston and the roll, fast and loose pulleys arranged on a shaft, gearing between said shaft and the rolls, a pair of belts leading to the pulleys, a belt-shifter for controlling the position of the belts to operate the rolls in normal or reverse direction, a valve controlling the admission of fluid pressure to the cylinder, said valve being carried by a rotary stem, an arm mounted on the stem and provided with a yoke, a rotary shaft carrying a crank arm in co-operative engagement with the yoke, a segmental gear mounted on said shaft, an operating member operatively connected to said segmental gear, and means for actuating the operating member.

DANIEL M. COOPER.
